ICE CARRIER

Bert C. Hosselkus, St. Louis, Mo., assignor to
 Leroy B. Barber, trading under the name of
 Vivian Manufacturing Company, St. Louis, Mo.

Application April 30, 1936, Serial No. 77,163

1 Claim. (Cl. 224—45)

This invention relates to receptacles especially designed for the delivery of ice.

Various carriers and receptacles have been designed for carrying ice from the delivery wagon 5 to the customer's refrigerator. In using many of these carriers it is necessary to place them on the floor of the home and to transfer the ice from the carrier to the refrigerator with the aid of ice tongs or the hands. Since dirt may collect on the bottom of the carrier the floor of the 10 home is often soiled by placing it on the floor. While it is possible with some of the available types of ice carriers to transfer the ice to the refrigerator directly from the carrier, the sides of 15 the box are often chipped or scratched in the transferring process. Many of the carriers designed for direct transfer of the ice from carrier to the box may be used satisfactorily with the so-called "side-icer" refrigerator, but cannot 20 be satisfactorily used to transfer ice into a "top-icer" refrigerator.

It is an object of this invention to provide a carrier for the delivery of ice which will overcome the above set forth disadvantages.

25 Thus one object of this invention is to provide an ice carrier from which the ice may be transferred to a refrigerator without the use of tongs or without placing the carrier on the floor.

Another object of this invention is to provide 30 an ice carrier from which ice may be transferred to a refrigerator without scratching or marring the finish of the refrigerator.

Another object of this invention is to provide 35 an ice carrier from which the ice may be transferred to a refrigerator and yet not allow water or dirt to get onto the floor.

Another object of this invention is to provide 40 an ice carrier adapted for use with the "top-icer" type of refrigerator.

Another object of this invention is to provide 45 an ice carrier adapted for use in placing ice into either a "top-icer" or a "side-icer" type of refrigerator.

Another object of this invention is to provide 50 an ice carrier with a means to prevent the shifting of the ice in the carrier while it is being carried from the delivery wagon to the refrigerator.

Yet another object of this invention is to provide 55 an ice receptacle which may be filled at the delivery vehicle without placing it on the ground.

Still another object of this invention is to provide 60 an ice carrier which may be carried on the operator's shoulder from the delivery vehicle to the refrigerator.

55 Further objects and advantages will appear

from the following description and accompanying drawings.

In the accompanying drawings, like numerals are employed to designate similar parts, and

Figure 1 is a perspective view of one form of 5 ice carrier embodying my invention;

Figure 2 is a cross sectional view taken along line 2—2 of Figure 1;

Figure 3 is a cross sectional view taken along line 3—3 of Figure 1; 10

Figure 4 is a cross sectional view taken along line 4—4 of Figure 1;

Figure 5 is a cross sectional view taken along line 5—5 of Figure 1; 15

Figure 6 is a cross sectional view taken along line 6—6 of Figure 2;

Figure 7 is a perspective view of another form of my invention;

Figure 8 is an end view of the receptacle shown 20 in Figure 7; and

Figure 9 is a top plan view of the receptacle shown in Figure 7.

Referring now to the drawings, the ice carrier or receptacle 2 may be formed from a single or multiple ply waterproofed duck, rubberized 25 material, or thin sheet metal. A side wall 4, end walls 6 and 8, and an extended side wall 10 extend upwardly from a bottom 12 to form a receptacle of substantially rectangular shape. The extended side wall 10 extends above the 30 upper edges of the opposite side wall 4. Extensions or flaps 14 of the extended side wall slope downwardly towards the ends of the end walls adjacent the side 4 and may be secured to the end walls by rivets 16 or by other means effective for the same purpose. In order to make the receptacle water tight, the walls and bottom may be formed from a single piece of suitable material, the corners being formed by overlapping triangular portions of the material 18 and securing them to the walls by rivets 19 to form a box-like receptacle with leak proof corners. Handles 20 of heavy webbing may be secured to the end walls by rivets 22. A ring 24 which may be secured to the carrier by a loop of webbing 25 45 held by the rivet 26, is useful in hanging the receptacle in the delivery vehicle. In the embodiment of the invention shown in the drawings, a double-ply waterproofed canvas used as a construction material for the bottom, extended side 50 and end walls, while the front side wall 4 was made three plies thick by extending and doubling over one of the plies of the double ply material, as shown in Fig. 2. A felt pad 28 may be held in the bottom of the receptacle between the plies 55

55

36 and 32 of the waterproofed canvas by stitching 34. A reinforcing means 36 is secured to the top edges of the walls and extensions and comprises a rope 38 bound by webbing 40 and sewed 5 to the top edges as shown. A strip of webbing 42 is sewed to the upper edge of the extended side to protect the side and the reinforcing means. Strips of webbing 44 are sewed across the bottom and extended side of the receptacle and serve 10 as bumpers to protect the material thereof from extreme wear as well as to stiffen the receptacle. Various other means may be used to stiffen the receptacle and the extended side wall, as by stitches 45 extending across the extended side 15 wall, ropes 46 may be sewed into the corners of the extended side wall and ropes 47 sewed under the strips of webbing 44.

The above described carrier is particularly designed for delivery of ice to the so-called "top-icer" refrigerator. In using this carrier the operator places the desired piece of ice on end at the rear end of the bed of the delivery vehicle, with one end of the ice extending a short distance over the end of the bed. The carrier is 20 turned sidewise and slipped over the portion of the ice cake extending over the edge of the vehicle bed. The operator may then place his shoulder next to the bottom of the receptacle and lift the same to his shoulder with the extended side of the receptacle at the outside of his shoulder and the other side wall adjacent his head. One hand of the operator will be free while the other hand is used to balance the receptacle on his shoulder. The padding in the 25 bottom of the receptacle serves to protect the operator's shoulder while he is transporting the ice in the above manner. Upon reaching the refrigerator the operator may use his free hand to open the door and make room for the ice, 30 after which he grasps the forward handle on the end wall of the carrier with his free hand and moves the hand which he was using to balance the carrier to the rear handle. He then lifts the carrier from his shoulder, turning and 35 lowering it so that the extended side rests on the lower sill of the refrigerator door opening. By tilting the bottom of the bag, the ice will slide on the extended side into the refrigerator. Any drippings or chips of ice will either go into the 40 refrigerator or remain in the bag and will not drop onto the floor. The extended side of the carrier protects the surface of the refrigerator opening and prevents any scratching or marring which might be caused by the sharp edges of the 45 ice.

The reinforcing means 36 around the top edges of the bag serves to hold the bag rigid as well as to retain in the receptacle any water which might accumulate therein until it can be conveniently emptied. The strips of webbing 44 serve as slides for the ice and thus save the bottom and extended side from extreme wear.

Another form of the invention is shown in Figures 7, 8 and 9 where the numeral 50 designates a receptacle similar to the one above described, but suited for delivery of ice to both top and side icer types of refrigerators. In this form of the invention, one of the extensions or flaps 14 is made higher and larger so that an extended end wall 52 is formed. This extension continues 55 around the corner of the adjacent end wall 6 and side wall 4 opposite to the extended side wall 10 to slope downwardly towards the upper edge of the side wall 4 forming an extended slop-

ing portion 54 on the side wall 4. Handles 56 and 58 may be secured by rivets 59 in the position shown. A strap 60 may be sewed to the bottom 12 of the receptacle and adjustably secured as by a loop 62 to the extended end wall 52. This strap is useful when a size of ice cake smaller than the receptacle is to be delivered. The small ice cake may be placed under this strap and the strap tightened thereon to prevent it from sliding back and forth in the receptacle while it is 10 being carried. When the strap is not used, it may be folded and placed at the bottom of the receptacle out of the way. The bottom corners of the carrier may be protected by reinforced corners 63 which may be of leather and sewed 15 to the receptacle. In using the above described bag for delivery of ice to a "top-icer" refrigerator, the operations are the same as outlined for the previously described type of ice carrier. In placing the carrier on the ice at the 20 delivery vehicle, the extended end wall should be placed on the top end of the ice cake as it rests on the wagon bed.

When ice is to be delivered to a "side-icer" refrigerator, the operator removes the carrier and 25 its contents from his shoulder by the handles 56 and 58 and lowers it until the extended end wall 52 rests on the lower sill of the refrigerator door opening and the ice is slid into the box 30 as before, the extended end wall now serving the same purpose as the extended side wall in the previously described carrier.

In both types of receptacle described, the use of tongs in the customer's house is dispensed with as is also the necessity of placing the bag 35 on the floor with the attendant transfer of dirt from the bottom of the bag to the floor. The use of either type of receptacle also insures that neither drippings nor chips from the ice will fall onto the floor in the process of transferring 40 the ice from the delivery truck to the refrigerator. The refrigerator is also well protected from the sharp and hard corners of the ice by the heavy material of the receptacle.

Since the carrier is adapted to be loaded at 45 the level of the delivery vehicle bed and carried on the operator's shoulder to the refrigerator to which the ice is transferred, without placing the carrier on the floor, the energy expended on raising the ice carrier to the shoulder from the ground at the delivery vehicle and in lifting the ice from the floor to the refrigerator which is necessary with other methods of ice delivery is 50 advantageously conserved.

While several embodiments of my invention 55 have been described, I do not desire my invention to be limited thereby but to be defined by the appended claim.

I claim:

An ice carrier adapted to be carried on an 60 operator's shoulder provided with a bottom, side and end walls extending upwardly from the bottom to form a receptacle, one of said sides and an end wall adjacent thereto extending substantially above the other end wall, a restricting 65 means adapted to prevent the extended side from folding in a direction outwardly from said receptacle, and a strap having one end secured substantially centrally of the bottom and its other end secured over the upper edge of the extended 70 end wall, one of said ends being adjustably secured.

BERT C. HOSSELKUS.
